PATENTED JUNE 30, 1903.

G. H. KLEMM.

INSERTIBLE CLOSURE FOR LIQUID RECEPTACLES.

APPLICATION FILED MAR. 4, 1903.

NO MODEL.

UNITED STATES PATENT OFFICE.

GEORGE HENRY KLEMM, OF FOWLER, COLORADO.

INSERTIBLE CLOSURE FOR LIQUID-RECEPTACLES.

SPECIFICATION forming part of Letters Patent No. 732,565, dated June 30, 1903.

Application filed March 4, 1903. Serial No. 146,080. (No model.)

To all whom it may concern:

Be it known that I, GEORGE HENRY KLEMM, a citizen of the United States, and a resident of Fowler, in the county of Otero and State of Colorado, have invented new and Improved Features of Construction for an Insertible Closure for Liquid-Receptacles, of which the following is a full, clear, and exact description.

10 The object of this invention is to provide novel details of construction for the closure of a liquid-package, such as a filled bottle or other receptacle having a neck, which will effectively prevent the refilling of the bottle 15 after its contents have been removed.

The invention consists in the novel construction and combination of parts, as is hereinafter described, and defined in the appended claims.

20 Reference is to be had to the accompanying drawings, forming a part of this specification, in which similar characters of reference indicate corresponding parts in all the figures.

Figure 1 is a vertical sectional view of the 25 invention applied to a bottle-neck, showing details in closed adjustment, the section being substantially on the line 1-1 in Fig. 4. Fig. 2 is a similar view, but showing the bottle-neck inverted and parts therein adjusted 30 to open a passage therethrough. Fig. 3 is a transverse sectional view substantially on the line 3-3 in Fig. 1. Fig. 4 is an enlarged transverse sectional view substantially on the line 4-4 in Fig. 1. Fig. 5 is a transverse sectional 35 view substantially on the line 5-5 in Fig. 1, and Fig. 6 is a side view of the bottle-closure and of a clamping-ring therefor.

In the drawings that show the construction and application of the improvement, A represents the neck of a bottle, and B the portion 40 of the body of the bottle from which said neck projects, these parts being of any preferred size and formed of glass or other suitable material. The neck A may with advantage be

45 formed cylindrically and have sufficient length to receive the improved closure, together with an ordinary cork C, the latter being inserted into the neck at its pouring end to seal the bottle and prevent an improper 50 escape of the liquid contents when the bottle is inverted, the improvement being designed

only to seal the bottle from an introduction of liquid and permitting the removal of the contents of the bottle when it is partly or entirely inverted, as will hereinafter be more 55 fully explained.

The body of the improved closure consists of a plurality of similar segmental blocks formed of glass or other suitable material. As shown, there are three of such sections 10 provided. Each piece 10 is of a length proportioned to the length of the neck A, and on the side which in service has contact with the interior wall of the neck A is rendered convex throughout its extent, the degree of convexity 65 of the three pieces or sections 10 producing a cylindrical contour for these closure-sections when they are joined together edgewise.

To enable the proper assembling of the similar closure-sections 10, the side edges of 70 each of said segments are sloped to give the block wedge form, said converging side edges being on lines that are radial from the axial center of the cylinder formed when the closure-sections are held together with their 75 edges in contact, as indicated at a in Figs. 4 and 5. Each closure-section 10 is similarly concaved at and near each end thereof, these concavities forming circularly-walled 80 passages b, c, respectively at the upper and lower ends of the closure-body when the three sections 10 are joined together.

Directly below the upper concavity b in each closure-section 10 a plurality of recesses d are formed, which are spaced apart by the 85 longitudinally-extended ribs e, these ribs and recesses extending to a point near the longitudinal center of the closure-section, where they terminate in a transverse concave flange g. From the flange g, that is of a suitable 90 width, a plurality of recesses d', formed in the closure-sections, extend toward and terminate in the defining-wall of the concavity c, said recesses d' being spaced apart by the longitudinal ribs e'.

The ribs e at their upper ends have their edges level with the surface of the concave wall b, and at b', a short distance below the upper terminations of the ribs e, said ribs are reduced in height, this reduction in height of the ribs extending to the cupped upper surface of the flange g, which latter is thus

adapted to serve as a valve-seat when the closure-sections 10 are joined together at their edges.

The ribs e' at their upper ends equal in height that of the upper ends of the ribs e , and a short distance below the valve-seat g , as at e^2 , the ribs e' are reduced in height, this reduction in height of said ribs continuing to a concavity c' in the upper surface of the defining-wall of the passage formed at c near the lower end of each section 10, which affords a valve-seat when these closure-sections are joined together to form a cylindrical hollow plug.

15 In the space between the main portions of the ribs e a globular valve 11 is introduced and seats upon the valve-seat g when the assembled sections 10 of the closure are disposed upright, and it will be seen that the 20 ribs e form guides for the valve and that the recesses d afford passages for liquid when the valve is removed from said valve-seat. A similar spherical valve 12 is introduced into the space below the valve-seat g , that is defined by the ribs e' and recesses d' , said valve by its gravity falling upon the annular valve-seat c' when the closure device is upright.

In the exterior surface of the three closure-sections 10 at an equal distance from their 30 upper ends a circumferential channel h is formed, and in the inner surface of the bottle-neck A a similar channel h' is produced, these channels when positioned oppositely by a proper insertion of the assembled sections 35 10 within the bottle-neck affording an annular keeper-groove, wherein a circular spring 13 may be located. The spring 13 may be of any preferred form in cross-section. As shown, it is a flat strip of resilient material, 40 which may be first placed in the channel h to hold the closure-sections 10 loosely connected together and subsequently be introduced within the mating channel h' by the insertion of the sections 10 and the spring encircling 45 the same within the bottle-neck until the spring comes opposite the channel h' , whereupon the spring by expansion enters the channel and is located partially in each channel, whereby the closure-plug is secured in 50 the bottle-neck.

To facilitate the assembling of the closure-sections 10, a shallow recess is formed in one edge of each closure-section, and on the other edge thereof directly opposite said recess a 55 corresponding tongue m is formed, these tongues and recesses, which are equally distant from the upper ends of closure-sections, being engaged—that is, a tongue will enter an opposite recess in an adjacent closure-section when the sections are placed together 60 edgewise and have the channels h therein disposed as a continuous circumferential groove. The end portions of the closure-sections 10 below the lower valve-seat c' are similarly 65 chamfered, so as to bevel the inner edge toward the outer edge of the same, and thus adapt the closure-plug to permit the unim-

peded passage of all liquid held in the bottle through the lower end of the passage c when the neck A is inverted.

To fix the closure-plug in position and prevent leakage between the sections 10, any suitable cement may be thinly spread on the edges of said closure-sections before the valves are placed therein, and a thin coating 75 of cement may also be spread upon the exterior of the assembled sections 10, so that the liquid in the bottle cannot leak through between joints in the plug or between it and the inner surface of the bottle-neck.

80 It will be seen that the parts of the improved closure-plug may be quickly and conveniently assembled and inserted in the neck of a filled bottle or other receptacle having a channeled neck adapted to receive said plug 85 and be therein secured by the spring 13, as before explained, and the bottle be hermetically sealed by means of the cork C.

When a portion of or the entire contents of the bottle having the improvement is to be 90 removed, the cork C being displaced, an inclination of the bottle-neck A slightly beyond a horizontal plane will cause the spherical valves 11 and 12 to roll on the ribs $e e'$ toward the offsets b' and e^2 in the ribs $e e'$, and as the 95 grooves $d d'$ extend farther upward than said offsets it will be seen that liquid flowing from the bottle through the passage c will traverse the grooves d' and pass the valve 12, that rests on the offsets e^2 , into the grooves d , past the valve 11, that rests against the offsets b' on the ribs e , and thence out of the bottle-neck.

Upon restoring the bottle to an upright position the valves 11 and 12 instantly resume 105 their seated engagement with the valve-seats g and c' , and thus prevent an introduction of liquid into the bottle, as it will be evident that it will be practically impossible to hold both of the valves 11 and 12 off of their seats 110 and pour liquid past them into the neck A of the bottle.

Having thus described my invention, I claim as new and desire to secure by Letters Patent—

115 1. A closure-plug for a receptacle, comprising a plurality of segmental sections, convex on outer surfaces and concave on inner sides, the edges of said sections contacting throughout their length, each section having a plurality of longitudinal grooves, ribs spacing the grooves, a transverse concaved flange formed on the ribs between the ends thereof, providing a valve-seat, a like valve-seat at lower ends of the ribs, two spherical valves 120 respectively held loosely by the ribs above the valve-seats, and offsets formed on the ribs whereon the valves contact when the closure-plug is inverted.

2. The combination with a bottle-neck having an interior annular channel, of a closure-plug, comprising three segmental sections, convex on their outer surfaces and concave on their inner sides, the longitudinal edges of

said sections having tongue-and-groove connection, and contacting throughout their extent when the sections are together inserted in the bottle-neck, an annular channel formed in the outer side of the sectional closure-plug, a bent spring engaging within the channel in the plug and in the bottle-neck, each closure-plug having two sets of longitudinally-disposed grooves, spaced apart by ribs, said ribs being reduced in height near their upper ends, to produce offsets, a transverse concaved flange intervening the two sets of ribs and grooves, forming a valve-seat when the closure-sections are assembled, a similar valve-

seat at the lower terminations of the lower set 15 of ribs and grooves, and a spherical valve held loosely in the closure-plug, above each valve-seat, said valves sealing the valve-seats when the plug is upright, but having contact with the offsets on the ribs, to open a passage 20 through the plug when it is inverted.

In testimony whereof I have signed my name to this specification in the presence of two subscribing witnesses.

GEORGE HENRY KLEMM.
